G. A. HORSTKOTTE,
RADIATOR FUNNEL.
APPLICATION FILED NOV. 10, 1921.

1,420,039.

Patented June 20, 1922.

UNITED STATES PATENT OFFICE.

GARRY A. HORSTKOTTE, OF BEND, OREGON, ASSIGNOR TO ABBOTT, INCORPORATED,
OF BEND, OREGON, A CORPORATION OF OREGON.

RADIATOR FUNNEL.

1,420,039.

Specification of Letters Patent. Patented June 20, 1922.

Application filed November 10, 1921. Serial No. 514,305.

To all whom it may concern:

Be it known that I, GARRY A. HORSTKOTTE, a citizen of the United States, residing at Bend, in the county of Deschutes and State 5 of Oregon, have invented certain new and useful Improvements in Radiator Funnels, of which the following is a specification.

This invention relates to automobile accessories, and has particular reference to a 10 collapsible funnel carried by or within the neck of a radiator in position to be drawn upward for use in filling the radiator with water or to be shoved downward within the neck to permit the cap to be screwed on as 15 usual.

This invention constitutes an improvement over a radiator funnel, the application for patent on which was filed by William E. Abbott, on April 16, 1919, Serial No. 20 290,477, and renewed September 22, 1921.

Among the objects of the present improvement is to provide a construction adapted for quicker assemblage and more reliable form than the previous device, there being 25 no solder or the like employed in connecting the parts thereof.

Another object of the invention is to simplify the means for securing the fabric or the like constituting the main wall or body 30 of the funnel, especially at its lower end.

With the foregoing and other objects in view the invention consists in the arrangement and combination of parts hereinafter described and claimed, and while the invention is not restricted to the exact details 35 of construction disclosed or suggested herein, still for the purpose of illustrating a practical embodiment thereof reference is had to the accompanying drawings, in which like reference characters designate the same 40 parts in the several views, and in which—

Figure 1 is a vertical sectional view of a conventional radiator neck and cap, with the improved funnel in position therein.

Fig. 2 is a similar view with the cap removed and the funnel drawn upward in operative position.

Fig. 3 is a plan view of the funnel in the position of Fig. 2.

Fig. 4 is a horizontal section on the line 4—4 of Fig. 2.

Fig. 5 is an enlarged detail on the line 5—5 of Fig. 4.

Referring now more specifically to the drawings I indicate a radiator 10 having a

neck 11 to which is screw threaded a closure cap 12. These parts are or may be of any well known construction.

As in the previous invention the funnel comprises a flexible body portion 13 of fabric or its equivalent woven or otherwise formed with a large circular flaring upper end 14 and a relatively restricted lower end retained always within the neck. I also indicate a plurality of flexible stays 15, shown 60 as six in number and of spring material such as steel. Each of these stays has a hook shaped upper end 16 within which the upper edge 14 of the funnel is drawn and clamped. The lower end of each stay is provided with 70 an outward extension 17 calculated to serve as a stop in co-operation with an offset or shoulder 18 formed in the inside of the neck, when the funnel is drawn upward. The stays at some convenient point, about an 75 inch above the offsets 17, are provided with inwardly directed projections 19, which are easily formed therein during the cutting and the shaping of the stays, the normal shape of which is practically that of Fig. 2, the 80 upper ends thereof tending to spread apart to extend the mouth of the funnel automatically when the funnel is drawn upward.

Adjacent to the lower end of the funnel 85 are two co-operating members shown as an inner band 20 and an outer band 21. These bands are calculated to nest one within the other with a tight fit and are preferably of equal width vertically. The inner band is 90 provided with as many indentations, shown as rectangular holes 22, as there are stays, and the size of these holes corresponds to the size of the projections 19 of the stays. Since the stays are all of flat material of 95 equal width or cross section and the indentations 22 are formed of a width corresponding to the width of the stays, it follows that when the stays are applied parallel to one another around the outside of the inner band, 100 the projection of each stay extending into or lying within an indentation 22, and then with the outer band slipped thereover holding the projections in interlocking co-operation with the indentations, the stays can 105 neither move up or down nor tilt laterally around the centers of the indentations. With the outer band 21 drawn into place with a tight frictional or driving fit, not only can the stays not move in any direction with 110

relation to the bands but the outer band will be held in place without requiring solder or any other extraneous means to hold it in such position.

- 5 5 With the funnel body 13 formed of fabric or similar flexible material, its lower end may be conveniently and reliably held in position so as not to slip or creep upward along the stays, by means of a ring 23 of
- 10 10 such material as round wire of a size to fit within the lower end of the stays but not to pass upward through the inner band 20. The lower end of the funnel may be looped or hemmed around the ring 23 as indicated
- 15 15 by the stitches 24. The attachment of the funnel to the ring 23 is performed prior to the drawing of the upper edge 14 upward into the loops 16, and thus the funnel body 13 is reliably secured within the skeleton or
- 20 20 frame of the funnel.

I claim:

1. In a funnel, the combination with a bell shaped flexible body and a series of resilient stays to which the upper edge of the body is secured, of holding means for the lower portion of the stays comprising a pair of annular members one within the other, one of the annular members having holes therethrough while the stays have projections extending into said holes and held therein by the other annular member.
2. In a funnel, the combination with a flexible body and a series of spring stays of flat spring material to which the upper edge 35 35 of the body is secured, of means for holding the lower ends of the stays in predetermined spaced relation to one another, said holding means comprising a band having holes therethrough of a width corresponding to the 40 40 width of the stays, the stays being offset forming projections fitted into said holes, and means co-operating with the stays to hold the projections in said holes, thus pre-

venting movement of the stays in any direction with relation to said band.

45

3. A funnel comprising, in combination with a flexible body and a plurality of spring stays to which the upper edge of the body is secured, means to hold the lower ends of the stays in predetermined spaced relation to one another and comprising an annular member having for each stay an indentation and the corresponding stay having a projection extending thereinto, and means co-operating with all of the stays to hold the projections 50 50 thereof in said indentations.

55

4. A device as set forth in claim 3 in which the indentations consist of rectangular holes of a width equal to the width of the stays.

5. A device as set forth in claim 3 in 60 which the holding means for the stays consists of a band extending around the stays on the outside of the member having the indentations.

60

6. In a collapsible funnel, the combination with a flexible body and a series of resilient stays to which one end of the body is secured, of means for holding the opposite ends of the stays in definite spaced relation to each other, such means comprising a pair 70 70 of annular members held frictionally one within the other with the stays between them.

65

7. In a collapsible funnel, the combination of a flexible fabric body, means to hold the body in operative expanded position, said holding means including an annular member, and means to hold the lower end of the body in downwardly extended position, said last mentioned means comprising a ring to 80 80 which the end of the body is secured, said ring being of larger diameter than the interior of the annular member against which the ring is drawn.

75

In testimony whereof I affix my signature. 85
GARRY A. HORSTKOTTE.
